Primary Examiner — Susan Moon Lee(74) *Attorney, Agent, or Firm* — RatnerPrestia(57) **CLAIM**

The ornamental design for a scanner, as shown and described.

DESCRIPTION

FIG. 1 is a front perspective view of a scanner showing our new design;

FIG. 2 is a front view thereof;

FIG. 3 is a rear view thereof;

FIG. 4 is a left side view thereof; the right side view is a mirror image of the left side view;

FIG. 5 is a top plan view thereof;

FIG. 6 is a bottom plan view thereof;

FIG. 7 is a cross-sectional view thereof taken in the direction of arrows 7-7 in FIG. 2; and,

FIG. 8 is another perspective view thereof showing the scanner head in an extended position.

Broken lines and portions contained within broken lines are not claimed.

1 Claim, 5 Drawing Sheets(56)
